UNITED STATES PATENT OFFICE

167,941

GOLF CLUB HEAD

Alfred R. Jamison, Quantico, Va.

Application July 14, 1951, Serial No. 15,876

Term of patent 14 years

(Cl. D34—5)

To all whom it may concern:

Be it known that I, Alfred R. Jamison, a citizen of the United States, residing at Quantico, in the county of Prince William and State of Virginia, have invented a new, original, and ornamental Design for a Golf Club Head, of which the following is a specification, reference being had to the accompanying drawing, forming a part hereof.

Fig. 1 is a front elevational view of the golf club head showing my new design;

Fig. 2 is a side elevational view thereof.

I claim:

The ornamental design for a golf club head, substantially as shown.

ALFRED R. JAMISON.
